UNITED STATES PATENT OFFICE.

WILLIAM A. MICHELS, OF BEAVER, IOWA.

DESIGN FOR A HOG-RACK.

SPECIFICATION forming part of Design No. 26,001, dated September 8, 1896.

Application filed June 22, 1896. Serial No. 596,545. Term of patent 7 years.

To all whom it may concern:

Be it known that I, WILLIAM A. MICHELS, a citizen of the United States of America, and a resident of Beaver, in the county of Boone and State of Iowa, have invented a new Design for Hog-Racks for Wagons, of which the following is a specification.

The leading feature of my design consists in a paneled framework or outline, the panels of which are filled in with fretwork or metallic weaving having the intersections of the weave interlocked.

In the illustrations, Figure 1 is an elevation showing a hog-rack of my design mounted for use. Fig. 2 is an elevation of an end portion of my design.

In the design of the end portion the numeral 10 designates the top bar; 11, the bottom bar parallel with the top bar; 12, the left end bar at right angles to the top and bottom bars and fixed to the ends thereof, and 13 the right end bar parallel with the left end bar and also at right angles to the top and bottom bars and fixed at its ends to the ends of 25 said top and bottom bars opposite to the left end bar. 14 indicates a tie-rod whereby attachment may be had of the end portion to contiguous devices. The bars 10, 11, 12, and 13 form an outline or panel, which is filled in 30 with crossed wires 15 16, crossing at right angles, the wires 15 being horizontal and the wires 16 being vertical. The wires 16 are

formed with loops 17 on their upper ends and below the said loops to the lower ends of the wires are straight. The horizontal wires 15 35 are laterally bent at 18 at the points where they cross in front of the vertical wires 16 and are locked to the vertical wires by curved metallic washers, in which the laterally-bent portions 18 of the wires rest, the straight wires 16 being positioned between the bent portions 18 of the wires 15 and the washers 19. 40

In the design shown in Fig. 1, the design shown in Fig. 2 is duplicated three times, 45 with the exception of the tie-rods, and the ends of said tie-rods are shown as they would appear in the elevation.

In both the illustrations the spaces between the wires are shown to be approximately 50 square, with the corners of the squares cut off by the circular segments of the washers, thus making outlines of fretwork within the outlines of the bars, the loops of the vertical wires appearing above the upper bars of the 55 framework.

I claim as my invention—

The design for a hog-rack as herein shown and described.

WILLIAM A. MICHELS.
